MULTIPLE JET OIL LIFT

Filed Feb. 6, 1925

Fig. 1.

Patented Feb. 1, 1927.

1,616,220

UNITED STATES PATENT OFFICE.

JOSEPH L. GAWLEY, OF LOS ANGELES, CALIFORNIA.

MULTIPLE-JET OIL LIFT.

Application filed February 6, 1925. Serial No. 7,272.

This invention relates to improvements in pumps.

It is an object of this invention to provide an improved pump adapted to be lowered into the fluid and sand in the well in which a fluid is discharged upwardly through an orifice provided in the pipe so as to lift the well fluid therethrough, and to provide means whereby fluid may be discharged within the pipe at various intervals by means of booster nozzles so as to facilitate lifting the well fluid to the surface.

It is a further object of this invention to provide a pump adapted to be lowered within a well casing, and to provide an improved packing means adapted to form a seal between the pipe of the pump and the well casing at any level.

It is a still further object of this invention to provide an improved jet lift pump for lifting well fluid and sand upwardly through a pipe, and to provide means for preventing the fluid, which is discharged through the jet so as to lift the well fluid, from escaping into the formation when operation of the pump is discontinued.

With the foregoing and other objects in view which will be made manifest in the following detailed description and pointed out in the appended claims, reference is had to the accompanying drawings for an illustrative embodiment of the invention, wherein:

Figure 1 is a vertical section through a well showing the improved pump as being lowered therein;

Fig. 2 is a vertical section through a well, the pump being shown as having been lowered into the well and in operation;

Fig. 3 is a vertical section taken substantially on the line 3—3 of Fig. 2;

Fig. 4 is a horizontal section taken substantially on the line 4—4 of Fig. 2; and

Fig. 5 is a vertical section through one of the booster nozzles employed upon the pump of my improved construction.

Referring to the accompanying drawings wherein similar reference characters designate similar parts throughout, the well hole is indicated at 10, in which there is disposed a well casing 11, the lower end of which is perforated as indicated at 12 to provide a screen for the well fluid. The pump proper is adapted to be lowered into the well casing 11 and consists of a pipe 13 which is provided at its lower end with a suitable plug

14. The plug 14 has a bore 15 formed therein and an orifice 16. Below the constricted portion of the orifice 16, the plug 14 is flared or countersunk, as indicated at 17, and above the orifice 16 the plug 14 is countersunk, as at 18. About the lower end of the pipe 13 there is secured a sleeve 19 providing a shoulder 20 for a purpose hereinafter to be described.

The pipe 13 is formed of sections connected together by couplings, and one coupling is shown at 21. Below the coupling 21, a mandrel 22 is slidable upon the pipe 13. This mandrel presents an exterior tapered or conical surface 23, about which is placed a plurality of split rings 24 which have their exterior surfaces leaded or provided with other sealing or deformable material, as indicated at 25. About the lower end of the mandrel 22 there is a ring 26 which has pins 27 extending upwardly through apertures formed in the split rings 24 so as to maintain them in proper position and in alignment about the mandrel 22. The interior surface of the split rings 24 is tapered so as to be complementary to the tapered surface of the mandrel 22.

Upon the upper end of the mandrel 22 there is formed a recess 28, in which is disposed packing adapted to be compressed by a packing gland 29 which may be tightened toward the mandrel 22 by bolts or cap screws 30. The over-all diameter of the mandrel 22 and of the gland 29 is slightly less than the interior diameter of the well casing 11. Upon the upper surface of the gland member 29 there is placed a leather washer 31, which is held in place by the bolts 30. This washer, which may be of leather or other material, is of a diameter substantially equal to the interior diameter of the well casing 11, so that the edge of the washer has a comparatively close fit 100 within the well casing 11.

When the pump is lowered into the well within the casing 11, the mandrel 22 rests upon the shoulder 20 provided by the sleeve 19, and the split rings 24 are disposed about the mandrel in a contracted position, so that the diameter of the split rings 24 is slightly less than the interior diameter of the well casing 11, permitting the pump to be readily lowered within the well casing. When in this position, the washer 31 is the only portion of the pump in actual contact with the

interior surface of the well casing 11. Water or circulation fluid or other fluid pressure is provided within the well casing 11 about the pipe 13 above the mandrel 22 when the 5 mandrel has been lowered into the proper position. The washer 31 prevents the escape of fluid pressure downwardly to a great extent, although the washer 31 is not designed to make an absolutely tight fit with 10 the well casing. When the fluid pressure has been applied, the washer 31 causes the mandrel 22 to be urged downwardly by the fluid pressure against the shoulder 20. The pipe 13 is then given a quick lowering 15 movement, that is, the pipe 13 is allowed to drop a few inches very quickly. The mandrel 22, because of the fluid pressure upon the washer 31, quickly follows the pipe downwardly and is limited in its downward movement by the shoulder 20. As 20 there is no pressure upon the split rings 24, these rings, because of their inertia, do not drop as quickly as the pipe 13 and the mandrel 22. In this manner the mandrel 22 25 will be caused to move relatively to the rings 24 within it and because of its exterior tapered surface, it will cause the rings to be expanded against the interior surface of the well casing 11, and because of the lead 30 or packing 25, these rings will form a tight seal between the pipe 13 and the casing 11. When the rings 24 have been expanded so as to form the seal, the pipe 13 may be lowered within the mandrel until its lower end 35 is immersed within the well fluid in the bottom of the well.

A supply pipe 32 is disposed within the lower end of the pipe 13 and has its lower end extending through the aperture 15 in 40 the plug 14. The bottom of the supply pipe 32 is bent upwardly so as to provide a nozzle 33 positioned directly below the orifice 16 within the flared portion 17. The upper end of the supply pipe 32 extends upwardly within the pipe 13 to a point opposite the coupling 21. At this point, the supply pipe 32 is provided with a special fitting 34 which has an elbow or port extending through the coupling 21 and communicating with the chamber formed between the pipe 31 and the well casing 11. This port is indicated at 35 in Fig. 3. Above the port 35 there are arranged upon opposite sides passages 36, and a check 50 valve in the form of a metal cylinder 37 is adapted to slide downwardly so as to close the passages 36 and seat upon a seat 38. The movement of the check valve 37 is limited in its upward direction by a plug 55 39 having an aperture 40 formed therein communicating with the interior of the pipe 13. The fitting 34 is connected to the upper end of the supply pipe 32 by a collar 41. Upon the supply pipe 32 there are mounted 60 booster nozzles 42 in the form of upwardly 65

turned elbows. These booster nozzles communicate with the interior of the supply pipe and are provided with ball check valves 43 which are retained in position adjacent the end of the nozzle by a cage 44. 70 Booster nozzles 45 are mounted upon the pipe 13 above the coupling 21, and consist of upwardly turned elbows which communicate with the chamber provided between the pipe 13 and the well casing 11 above the mandrel 22. A ball check valve 46 is positioned within the flared portion 18 of the plug 14 and is adapted to close the orifice 16. The ball check valve 46 is maintained within the flared portion by a cage 47. 75 80

The operation of the pump is as follows: After the split rings 24 have been expanded to form the seal between the pipe 13 and the well casing 11, the pipe may be thrust downwardly within the mandrel 22 so that its lower end is immersed in the well fluid. The fluid pressure within the chamber between the pipe 13 and the well casing 11 above the mandrel 22 enters the port 35 below the check valve 37 which is seated upon the seat 38. This fluid pressure, which is greater than the pressure which may be developed by the column of liquid within the pipe 13, lifts the check valve 37 and the fluid passes through the passages 36 downwardly within the supply pipe 32. Part of the fluid which enters the supply pipe 32 beneath the check valve 37 is discharged upwardly through the orifice 16 by the nozzle 33, lifting the ball check valve 46 and drawing the well fluid upwardly with it through the orifice 16. Some of the fluid in the supply pipe 32 is discharged in an upward direction through the booster nozzles 42, lifting the ball check valves 43. In this manner the well fluid is caused to enter the pipe 13 and to be lifted therein by the nozzle 33, and the lifting is assisted by the booster nozzles 42. Fluid in the chamber between the pipe 13 and the well casing 11 110 enters the pipe 13 and is discharged upwardly by the booster nozzles 45, in this manner assisting the lifting of the well fluid within the pipe. 115

Although any fluid, such as compressed air, or compressed gas, may be employed, the improved pump is especially adapted for use in pumping oil from oil wells, and the preferred fluid in such cases is water, which not only has the effect of gas in lifting the oil, but also because of the fact that the water is heavier than oil, causes the oil to tend to float upon the water and rise within the pipe 13. 120

Many of the States have enacted statutes which prohibit using a jet lift pump of this construction which lifts the oil by pumping water into the well, because of the fact that if the fluid should fail to rise within the pipe 13, the water would be pumped into 125 130

the formation or oil sand. To employ the pump of the improved construction in the States having such statutes, the check valves 37, 43 and 46 are employed. The check valves 43 and 46 prevent the escape of well fluid and water from the pipe 13 into the supply pipe 32 and into the well casing, and in this manner water in the well fluid cannot escape into the formation or oil sand. The 10 release of the pressure in the chamber between the pipe 13 and the well casing 11 above the mandrel 22 allows the check valve 37 to seat because of its own weight, it being understood that the hydraulic pressure 15 developed outside of the pipe 13 is approximately equal to the hydraulic pressure inside of the pipe 13, and these pressures because of the port 35 and the aperture 40 are applied to the opposite sides of the valve 37. 20 In this manner release of the pressure allows the check valve 37 to fall and will prevent the water within the chamber between the pipe 13 and the well casing 11 to pass downwardly through the supply pipe 32 and into 25 the formation. The amount of fluid which is within the supply pipe 32 upon release of the pressure does flow downwardly in some cases through the supply pipe and into the well casing 11 below the plug 14. However, this amount of water is small and is 30 not objectionable.

The advantages of this type of pump are that the jet 33 not only efficiently lifts the oil when aided by the booster nozzles 42 and 45, but also will cause the oil to carry sand with it and in this manner sanding up of the well is effectively prevented.

When it is desired to pull the pump from the well, the pipe 13 is merely lifted, causing the shoulder 20 to engage the lower end of the mandrel 22, so as to cause it to slide upwardly within the split rings 24, and in this manner the split rings, because of their own resiliency, will contract, enabling the 45 pump to be readily pulled from the well casing 11.

From the above it is seen that an improved pump is provided which is capable of being lowered into a well which may be even 50 completely sanded up, and that the pump will lift the sand in the bottom of the well, clear out the well and pump the oil which enters the well hole after the sand has been removed. It will be readily understood that 55 when the well hole is sanded up, the bottom of the pipe 13 is lowered upon the top of the sand and operation is commenced. This lifts the sand around the bottom of the pipe 13 and as the sand is removed, the pipe 60 13 may be lowered through the mandrel 22 so as to follow the sand down to the bottom of the well hole, and thus completely clear out the well hole and pump the oil or other well fluid. By using both the jet 33 and the 65 booster nozzles the pump may be employed

in very deep wells which may be 5,000 feet deep more or less, and this makes the pump useful in wells of greater depth than those in which prior jet lift pumps have been employed.

It will be understood that various changes in the detail of construction may be made without departing from the spirit or scope of the invention as defined by the appended claims.

I claim:

1. A pump comprising a well casing, a pipe disposed within said well casing, a mandrel slidable upon said pipe, packing means slidable upon said mandrel adapted to be expanded upon downward movement of said mandrel relatively thereto so as to form a seal between said pipe and said casing, a shoulder provided upon said pipe below said casing engageable upon said mandrel, and booster nozzles arranged at various intervals within said pipe above said mandrel whereby fluid pressure may be admitted to said pipe from within said casing and discharged in an upward direction therein.

2. A pump comprising a well casing, a pipe disposed within said well casing, a mandrel slidable upon said pipe, packing means slidable upon said mandrel adapted to be expanded upon downward movement of said mandrel relatively thereto so as to form a seal between said pipe and said casing, a shoulder provided upon said pipe below said casing engageable upon said mandrel, a supply pipe disposed within said pipe, means including a check valve providing a connection between said supply pipe and the exterior of said pipe, an orifice provided adjacent the bottom of said pipe, and an upwardly directed nozzle provided upon said supply pipe, whereby fluid may flow downwardly between said pipe and said casing, enter said supply pipe and be discharged in an upward direction through said orifice so as to lift the liquid about said pipe through said orifice.

3. A pump comprising a well casing, a pipe disposed within said well casing, a mandrel slidable upon said pipe, packing means slidable upon said mandrel adapted to be expanded upon downward movement of said mandrel relatively thereto so as to form a seal between said pipe and said casing, a shoulder provided upon said pipe below said casing engageable upon said mandrel, a supply pipe disposed within said pipe, means including a check valve providing a connection between said supply pipe and the exterior of said pipe, an orifice provided adjacent the bottom of said pipe, an upwardly directed nozzle provided upon said supply pipe whereby fluid may flow downwardly between said pipe and said casing, enter said supply pipe and be discharged in an upward direction through said orifice so as to lift the liquid about said pipe through said ori-

ifice, and a check valve adapted to close said orifice so as to prevent downward flow of fluid therethrough.

4. A pump comprising a well casing, a pipe disposed within said well casing, a mandrel slidable upon said pipe, packing means slidable upon said mandrel adapted to be expanded upon downward movement of said mandrel relatively thereto so as to 10 form a seal between said pipe and said casing, a shoulder provided upon said pipe below said casing engageable upon said mandrel, a supply pipe disposed within said pipe, means including a check valve providing a connection between said supply pipe and the exterior of said pipe, an orifice provided adjacent the bottom of said pipe, an upwardly directed nozzle provided upon said supply pipe, whereby fluid may flow downwardly between said pipe and said casing, enter said supply pipe and be discharged in an upward direction through said orifice so as to lift the liquid about said pipe through said orifice, and booster nozzles 25 mounted upon said supply pipe for directing fluid from said supply pipe upwardly within said pipe above the bottom thereof.

5. A pump comprising a well casing, a pipe disposed within said well casing, a mandrel slidable upon said pipe, packing means slidable upon said mandrel adapted to be expanded upon downward movement of said mandrel relatively thereto so as to 30 form a seal between said pipe and said casing, a shoulder provided upon said pipe below said casing engageable upon said mandrel, a supply pipe disposed within said pipe, means including a check valve providing a connection between said supply pipe and the exterior of said pipe, an orifice provided adjacent the bottom of said pipe, an upwardly directed nozzle provided upon said supply pipe, whereby fluid may flow downwardly between said pipe and said 35 casing, enter said supply pipe and be discharged in an upward direction through said orifice so as to lift the liquid about said pipe through said orifice, booster nozzles 40

mounted upon said supply pipe for directing fluid from said supply pipe upwardly within said pipe above the bottom thereof, and check valves adapted to close said booster nozzles and orifice so as to prevent flow from said pipe therethrough.

6. A pump comprising a well casing, a pipe disposed within said well casing, means for forming a seal between said pipe and said well casing, means providing an orifice adjacent the bottom of said pipe, a supply pipe disposed within said pipe and provided with a nozzle for discharging a fluid therefrom upwardly through said orifice, said supply pipe communicating with the exterior of said pipe above said seal, booster nozzles mounted upon said supply pipe discharging fluid in an upward direction within said pipe, and booster nozzles mounted upon the interior of said pipe above said seal whereby fluid between said pipe and said casing may be discharged therethrough 50 55 60 65 70

7. A pump comprising a well casing, a pipe disposed within said well casing, means for forming a seal between said pipe and said well casing, means providing an orifice adjacent the bottom of said pipe, a supply pipe disposed within said pipe and provided with a nozzle for discharging a fluid therefrom upwardly through said orifice, said supply pipe communicating with the exterior of said pipe above said seal, booster nozzles mounted upon said supply pipe discharging fluid in an upward direction within said pipe, booster nozzles mounted upon the interior of said pipe above said seal whereby fluid between said pipe and said casing may be discharged therethrough 75 80 85 90 95

In testimony whereof I have signed my name to this specification.

JOSEPH L. GAWLEY.
